Primary Examiner — Carla Jobe Wright*Assistant Examiner* — Holly E Thurman(74) *Attorney, Agent, or Firm* — Kirk A. Buhler; Buhler & Associates(57) **CLAIM**

The ornamental design for a self-tightening holding strap, as shown and described.

DESCRIPTION

FIG. 1 is a top perspective view of a self-tightening holding strap showing our new design;

FIG. 2 is a front side view thereof;

FIG. 3 is a top side view thereof;

FIG. 4 is a back side view thereof;

FIG. 5 is a bottom side view thereof;

FIG. 6 is an enlarged left side view thereof;

FIG. 7 is an enlarged right side view thereof;

FIG. 8 is a top perspective view thereof shown in an environment of use; and,

FIG. 9 is a top perspective view shown in an environment of use.

The broken lines shown in FIGS. 8 and 9 depict unclaimed environmental subject matter only, which forms no part of the claimed design.

The weave pattern, hatch-like, and stippled shading shown in FIGS. 1 through 9 indicate woven material, hook material, and loop material respectively.
